(57) **CLAIM**

The ornamental design for a disc pet chew, as shown and described.

DESCRIPTION

FIG. 1 is a front, top and right side perspective view of a first embodiment of a disc pet chew according to the new design; FIG. 2 is a front elevation view thereof; FIG. 3 is a back elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a back, bottom and right side perspective view thereof;

FIG. 9 is front, top and right side perspective view of a second embodiment of a disc pet chew according to the new design;

FIG. 10 is a front elevation view thereof;

FIG. 11 is a back elevation view thereof;

FIG. 12 is a left side elevation view thereof;

FIG. 13 is a right side elevation view thereof;

FIG. 14 is a top plan view thereof;

FIG. 15 is a bottom plan view thereof;

FIG. 16 is a back, bottom and right side perspective view thereof;

FIG. 17 is a front, top and right side perspective view of a third embodiment of a disc pet chew according to the new design;

FIG. 18 is a front elevation view thereof;

FIG. 19 is a back elevation view thereof;

FIG. 20 is a left side elevation view thereof;

FIG. 21 is a right side elevation view thereof;

FIG. 22 is a top plan view thereof;

FIG. 23 is a bottom plan view thereof; and,

FIG. 24 is a back, bottom and right side perspective view thereof.

The broken lines in the drawings illustrate portions of the disc pet treat that form no part of the claimed design.

The break lines shown in the middle portion of the disc pet treat in FIGS. 17-24 indicate that the appearance of any portion of the article between the break lines forms no part of the claimed design.

1 Claim, 15 Drawing Sheets
